FREQUENCY STABILIZATION OF
MAGNETRONS

William M. Preston, Lincoln, Mass., assignor, by
mesne assignments, to the United States of
America as represented by the Secretary of
War

Application September 19, 1945, Serial No. 617,317

1 Claim. (Cl. 250—36)

1

My invention relates in general to apparatus for stabilizing electrical generators and more particularly to such apparatus which is associated with high frequency electron oscillating apparatus.

In the use of oscillators or generators employing thermionic tubes such for instance as the magnetron, it has been found that the electrical properties thereof vary to a considerable degree and some means of stabilizing the frequency of the apparatus is necessary. Maintaining adequate frequency stabilization is very difficult because the frequency of a magnetron varies with the magnetic field, radio frequency load, peak current and temperature. This is in addition to the fact that magnetrons are not identical when they are manufactured. These effects will cause an undesirable change in magnetron frequency and accordingly means must be developed to influence the frequency in such a fashion that it is comparatively stable. Accordingly, it is one of the objects of my invention to provide such an apparatus.

The stabilizing of the tube can be influenced by apparatus which controls or influences the tuning of the magnetron. Accordingly, it is another of the objects of my invention to provide an apparatus in which the tuning of the magnetron may be influenced by apparatus external thereto.

In the stabilizing apparatus per se, it has been found necessary to decrease the danger of obtaining arcs of radio frequency energy resulting from the currents involved in the apparatus passing into very high impedance such for instance as found when a resonant cavity type of stabilizer is used. Accordingly, it is another of the objects of my invention to provide an apparatus in which this danger may be minimized because for some frequencies it may be possible to accomplish the result of this preceding paragraph by inserting a resistive load in series with the resonant cavity used. However, when ultra-high frequencies are used it has been found that special means must be provided for accomplishing this result. Heretofore dissipative loads such as sand have been used to some degree but have not been found to be the answer to the problem when ultra-high frequencies are developed and utilized. Accordingly, it is another of the objects of my invention to provide such a load arrangement which may be used in conjunction with the resonant cavity for use in a system such as described hereinafter.

In general, my apparatus contemplates the provision of a generator employing thermionic

2

apparatus such for instance as a magnetron type of tube. The magnetron may be coupled to a main wave guide which is adapted to furnish energy to a radiating structure. Cut in the main wave guide is a slot or open section and a second or branch wave guide is provided which embraces the opening in the main guide and is adjustable relatively thereto. Connected to the branch guide is a resonant cavity whose parameters are adjustable. The output of the branch guide may be fed into a lumped load or dummy load for matching purposes. Inserted in the branch guide at a position remote from the end thereof into which energy is fed is an inductive diaphragm which will be referred to more fully hereafter. The movement of the branch guide and its associated resonant cavity will affect or influence the tuning of the magnetron.

My invention will best be understood by reference to the drawings, in which:

Fig. 1 shows one embodiment of my invention schematically;

Fig. 2 is a showing of the main wave guide with a slot therein;

Fig. 3 is a perspective view of a branch guide with its associated resonant cavity;

Fig. 4 shows a dummy load with its arrangement for coupling to the branch guide; and

Fig. 5 is a cross section of an inductive diaphragm.

Referring to Fig. 1, there is shown one embodiment of my invention. In this figure an ultra-high frequency generator such for instance as the magnetron 10 has coupled thereto a coupling device 11 for the purpose of passing energy to a main wave guide 12. The entire structure of the latter is not shown, but is merely indicated as feeding energy to a radiating means identified by the term antenna. The main guide has an open section or slot cut in one of the larger faces thereof and which will be more clearly shown in Fig. 2. Embracing the main guide is an apparatus 15 which is joined to a minor or branch guide 16. The face of the guide 12 being slotted for a portion of its length, energy may be fed through the slot to the branch guide 16. The supporting member 15 has joined thereto two spring members 17 and 18 which are adapted to press against the face of the main guide opposite to that which is slotted for the purpose of having the branch guide pull firmly into contact with the face of the main guide containing the slot.

Associated with the branch guide and fed thereby is a resonant cavity inclosed by the member 20 which has an opening thereof positioned

adjacent an opening in the branch guide so as to be fed thereby. This is identified in the drawing by the terminology "circular iris" and the iris is positioned a distance from the main guide which is an odd multiple of a quarter wavelength of the generated wave. Positioned within the branch guide and at a section thereof remote from the juncture from the main guide of the branch guide is an inductive diaphragm 25 and the end of the branch guide is terminated in a matching resistor 30.

Referring to Fig. 2, there is shown a perspective view of the main type of guide. This consists of substantially rectangular guide 12 having a slot 35 cut in one face thereof. The ends of the guide terminate mechanical coupling members 36 and 37. Also joined to one of the faces is a member 38 having a threaded aperture which is adapted to be engaged by a screw member for moving the branch guide relatively to the main guide.

Referring to Fig. 3, there is shown a perspective view of a branch guide with its associated resonant cavity. The resonant cavity 40 is adapted to have its parameters changed by turning of the dial knob 41. A scaled member 42 is positioned adjacent to dial knob for the purpose of indicating the parameters of the cavity at any one time. Mechanically joined to the cavity and adapted to feed the cavity is the minor or branch guide 16 one end of which has a mechanical coupling member 45 and the other end of which is fastened to member 46. The member 46 is adapted to embrace at least a portion of the main guide at the position thereof where the slot 35 is located and hence energy will pass through the slot through the branch guide. For purposes of clarity, the end plate containing the spring members 17 and 18 has been omitted from this drawing. Joined to the member 46 is a member 47 which is apertured and threaded and passing therethrough is a screw member 48 adapted to be turned by knob 49. The screw member engages the portion 38 of the main guide and turning of the knob will produce relative movement between the main guide and the branch guide.

Referring to Fig. 4, there is shown a dummy load arrangement for use with the branch guide for matching purposes. The mechanical coupling member 50 is adapted to be placed against the mechanical coupling member 45 of Fig. 3.

Referring to Fig. 5, there is shown a cross section the inductive diaphragm 25 which is positioned in the branch guide 16 as illustrated in Fig. 1.

In practice the correct setting of the cavity mount can be found quickly by detuning the stabilizing cavity a considerable distance either above or below the magnetron frequency. The sliding section may be moved in smaller incremental steps and at each position thereof magnetron frequency may be measured. As the cavity is moved away from the magnetron the frequency will decrease continuously to a minimum value and then jump abruptly to a higher value and again decrease. The correct position is that at which the frequency jump occurs. Since the operating frequency of the magnetron is pulled toward the resonant frequency of the resonant cavity the latter tends to stabilize the frequency to some extent. It is for this reason that the cavity assembly is called or may be referred to as a stabilizing tuner.

The use of minor guides as stabilizing elements has been known heretofore to the art to which this case belongs and the use of the resonant cavity associated with the minor guides also is known to the art. With the arrangement according to this invention, however, the slide unit moving back and forth across the slot in the wave guide 12 easily allows the positioning of the minor guide so that the distance "D" is adjusted very easily and further the resistive load 30 provided at the end of the guide makes the adjustment of the distance "D" less critical. In addition the inductive diaphragm is placed at such a position in the minor or branch guide 16 so that it appears as a resistance at the resonant cavity iris and likewise at the entrance to the main guide provided the guide beyond the diaphragm is terminated in a matched load.

It will be appreciated that there may be deviations from the particular showing of this invention which will still remain within the spirit and scope thereof. Accordingly, I claim all such departures as fall fairly within the spirit and scope of the hereinafter appended claim.

What is claimed is:

A magnetron tuning system comprising a magnetron, a major wave-guide, means for coupling said magnetron to said major wave-guide, said major wave-guide having a first aperture, a sliding sleeve fitting over said major wave-guide and said first aperture, a second aperture in said sleeve of smaller dimensions than the dimensions of said first aperture, a minor wave-guide fixed by fitting into said second aperture and opening into said major wave-guide, a cavity resonator electrically coupled to said minor wave-guide, an impedance matching device at the outer end of said minor wave-guide, said impedance matching device including a matching resistance connected to the end of said minor wave-guide and an inductive diaphragm positioned in said minor wave-guide near the end thereof so as to make said minor wave-guide appear as a resistance at the junction point of the major and minor wave-guides, a first means positioning said minor wave-guide substantially to a point on said major wave-guide at which the magnetron frequency jumps, and a second means for altering the resonance frequency of said cavity, the relative positions of said first and second means adjusting the frequency of said magnetron.
